UNITED STATES PATENT OFFICE.

PAUL J. RAY, OF LAKESIDE, OHIO.

SOUND-PRODUCING DIAPHRAGM.

1,315,411.

Specification of Letters Patent. Patented Sept. 9, 1919.

Application filed May 28, 1917. Serial No. 171,360.

To all whom it may concern:

Be it known that I, PAUL J. RAY, a citizen of the United States, residing at Lakewood, county of Cuyahoga, and State of Ohio, have invented certain new and useful Improvements in Sound - Producing Diaphragms, of which the following is a specification.

The object of the invention is to provide a diaphragm for sound boxes for use in recording and reproducing sound in connection with phonographs and similar instruments, whereby improved qualities and characteristics of tone, and better results in transmission and reproduction, are obtained, due consideration being given to questions of economy in production, cheapness of material, durability in use, and uniformity in results.

20 In the accompanying drawing:—

Figure 1 is a bottom plan view of a device embodying my improved construction.

Fig. 2 is a transverse sectional view of the same.

25 In the said drawing, the reference numeral 10 denotes a base, preferably of fibrous woven fabric, which may be either metallic or non-metallic, though I prefer to use silk, linen, or the like. However, any 30 other suitable material may be used, such as treated skins or tough paper. This base is mounted in an unbroken metallic ring 11, preferably circular in cross area, though said cross area configuration is not essential.

35 Said base is disposed in the ring under tension, the body thereof being carried around the ring, as shown at 12, and being attached thereto in any suitable manner, preferably by being sewed thereto, the thread 13 being

40 disposed spirally upon the ring 11, as best seen in Fig. 1. After the base has been attached to the ring 11, the same is provided with a filler or coating of plastic material, which may be applied either by dipping, 45 molding, or otherwise, so as to render said base resonant, while not detracting substantially from its flexibility or its other qualities which adapt it to yield readily to impulses of sound waves. A wide range of 50 materials and compositions may be used as the filler or coating, as for example, wax or resin, or both, in any of their forms.

The base 10 and its supporting ring 11, when so assembled, are adapted to be mount-

ed in any suitable sound box, preferably 55 clamped between elastic supports, whereby the device is capable of slight springing movement, and also is capable of a bodily vibration when the amplitude of nodal vibration of the base is excessive, thereby relieving said base and its coating or filler of 60 excessive strain. A further and important feature of the present invention is found in the fact that the ring 11 is formed of a single piece of material, which renders it to 65 some extent inherently susceptible to vibratory impulses, thereby enhancing the vibratory results obtained from the base 10.

It will be observed that the base 10 is flat, and that the flexible loops or stitching which 70 attach it to the ring so connect it that there is permitted to said base what may be termed a piston action or bodily vibration, such as would not be obtained were the fastening means applied to overlapped parts. 75

By mounting the base 10 upon an independent ring or frame of vibratory material, I eliminate any amplified frictional noise, and provide a separate article of manufacture which can be coated conveniently after being assembled, thus eliminating the objectionable features of diaphragms supported by the frame of the sound box.

Having thus described my invention, what I claim as new and desire to secure by Letters Patent, is:—

1. A sound producing diaphragm, comprising a ring, and a base mounted within said ring and united thereto by flexible loops. 90
2. A sound producing diaphragm, comprising a ring, and a base mounted within said ring and united thereto by stitching.
3. A sound producing diaphragm, comprising a ring, and a base of fibrous material 95 mounted within said ring and united thereto by stitching.
4. A sound producing diaphragm, comprising a ring, and a base mounted within said ring and united thereto by stitching applied thereto spirally. 100

This specification signed and witnessed this 26th day of May, A. D. 1917.

PAUL J. RAY.
